US00D997286S

(12) **United States Design Patent** (10) **Patent No.:** **US D997,286 S**
(45) **Date of Patent:** **** Aug. 29, 2023**

(54) **OPTICS COVER**

(71) Applicant: **Jinbao Ao**, Yangjiang (CN)

(72) Inventor: **Jinbao Ao**, Yangjiang (CN)

(**) Term: **15 Years**

(21) Appl. No.: **29/887,458**

(22) Filed: **Mar. 21, 2023**

(51) LOC (14) Cl. **22-01**

(52) U.S. Cl.

USPC **D22/109**; D22/199

(58) **Field of Classification Search**

USPC D21/567, 573, 575; D22/103, 105, 108,
D22/109, 110, 199

CPC F41A 35/00; F41C 23/16; F41C 27/22;
F41C 33/007; F41C 27/00; F41G 11/003

See application file for complete search history.

(57) **CLAIM**

The ornamental design for an optics cover, as shown and described.

DESCRIPTION

FIG. 1 is a perspective view of an optics cover, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the optics cover that form no part of the claimed design.

1 Claim, 8 Drawing Sheets
